THERMOSTATIC CONTROL MECHANISM

Joseph A. Cerny, Cleveland, Ohio, assignor to The
Titan Valve and Manufacturing Company,
Cleveland, Ohio, a corporation of Ohio

Application November 13, 1937, Serial No. 174,306

5 Claims. (Cl. 236—48)

This invention relates to improvements in thermostatic control devices and more particularly to an improved device permitting a very nice adjustment of temperature range.

An object of the present invention is the provision between a thermostatic element and a control member operable thereby of a lever engageable by the thermostatic element, and means for adjusting the distance between the thermostatic element and the lever comprising adjusting mechanism having a lever arm greater than the effective lever arm of the thermostatic element.

Another object of the present invention is the provision of a multiple leverage carried by a pivotally mounted support wherein the leverage provides an operative connection between a thermostatic element and a control member operated thereby, together with means for adjusting the support to various positions about its pivot for the purpose of varying the temperature which the control mechanism is intended to maintain.

In the specific embodiment herein disclosed, my invention provides a pivotally supported frame having two levers supported thereon and connected by a spring in such a manner that movement of one of the levers carries the spring from side to side of the fulcrum of the other lever whereby to produce a snap action control and a lever arm for adjustably positioning the supporting frame about its pivot so as to vary the action of the levers. Preferably the adjustment of the supporting frame about its pivot comprises a threaded member having sufficient leverage with reference to the pivotal mounting of the supporting frame to provide a very fine adjustment of the radial position of the frame about its pivot.

Other novel features of my improved device will be set forth in the specification and illustrated in the drawing and the essential features will be summarized in the claims.

In the drawing Fig. 1 is a sectional view of a thermostatic control mechanism embodying my device; Fig. 2 is a partial sectional view of the same mechanism showing the parts in a different position; while Figs. 3, 4 and 5 are detail perspective views of several parts of the lever mechanism.

I have illustrated my improved control mechanism as associated with a well known type of valve mechanism and associated parts adapted for use with gas fired devices. In the form shown, a casing or casting 10 is arranged with

suitable gas passages therethrough including a threaded connection for gas inlet at 11 and a threaded connection for gas outlet at 12. A main gas valve known to the trade as the "A" valve is indicated at 13 and a "B" valve or pilot valve at 14. In an intermediate partition 10a is provided a gas port 15 which is closable by the spring pressed valve 16. The spring 17 normally urges the valve to closed position. A thermostatic element 18 is adapted to enter the casing to cooperate with the control mechanism for the opening and closing of valve 16 in response to the temperature of the thermostatic element. The element shown comprises a tube 18a having a relatively large coefficient of expansion. To the outer end of this tube is secured a rod 18b having a relatively small coefficient of expansion. It results therefore when the thermostatic element is cooled that the tube 18a contracts and rod 18b moves toward the left as viewed in Figs. 1 and 2.

The control mechanism operatively connecting the thermostat 18 and the valve 16 comprises a multiple leverage carried by the support 19 which is adjustably mounted within the casing 10 by a pivotal mounting 20 between the members 10 and 19. Preferably, as shown in the various views, the upper portion of the member 19 is generally U-shape in form having pins 20 receiving openings for the pin 20 at the points 20a. The member 19 has bifurcated legs 19a extending downwardly and struck up between them is the portion 19b. Member 19 is normally stationary, i. e., it does not move during ordinary operation of the parts. However, it is adjustable about its pivot to vary the mean temperature which the control mechanism is intended to maintain, for which purpose, in the form shown, portion 19b is engaged and held by adjusting member 21 which is threaded at 22 in a boss 23 of the casing 10 and is provided at its outer end with an operating knob 24. The knob 24 is graduated on its face to coact with a fixed pointer 26a on casing 10. Pivotally mounted on the upper end of the member 19 by pin 25 is a main lever 26. This lever is adapted to engage with the thermostat rod 18b at the point 27. This point is accurately fixed in the main lever by a small depression which receives the sharpened end of rod 18b. At the lower end of support 19 at points 28 are fulcrumed the bifurcated legs 29a of a lever 29. As shown in the drawing, the lower ends of the legs 29a are provided with knife edges which rest in suitably formed grooves in the inwardly turned ends of

the legs 19a. The upper end 29b of the lever 29 passes through an opening 19c in the support 19 and is positioned to engage the end of valve 16. It will be noted that levers 26 and 29 are pivoted at opposite ends of the member 19 and extend generally toward each other. A spring 30 is connected between the free ends of levers 26 and 29 in such a manner that the spring is carried from side to side past the fulcrum 28 upon movement of lever 26 in response to the thermostatic element.

With the parts in the position of Fig. 1, the tube 18a of the thermostatic element has expanded because of the temperature rise until the rod 18b has moved to the right, lever 26 moves to the right under the influence of spring 30 carrying the axis of the spring to the right of point 28 and snapping lever 29 to the right thus permitting valve 16a to close and cutting off the fuel to the heater burner. Upon a cooling of the tube 18a it changes by contraction to a greater extent than the rod 18b, moving the rod 18b toward the left as viewed in Figs. 1 and 2, causing lever 26 to move in a clockwise direction about the pivot 25 until the axis of spring 30 has been carried to the left beyond the fulcrum 28, whereupon the spring causes movement of lever 29 counterclockwise about fulcrum 28 with a snap action, thus opening valve 16 and supplying fuel to the burner. This action continues until the thermostatic element again becomes heated, causing rod 18b to move to the right, moving spring 30 again to the position of Fig. 1, whereupon lever 29 returns in a clockwise direction permitting valve 16 to close.

A very fine adjustment of the temperature range of my improved control device is provided in the structure shown. It will be noted that the distance between the point 21a where member 21 engages 19b and the point 20 is much greater than the distance from the point 27 to the point 20, in fact it is over three times as great. This means that a movement of the arm 19b by means of adjusting member 21 will cause less than one-third of that adjusting movement at the point 27. Such an adjusting movement changes the movement of rod 18b necessary to cause actuation of valve 16. In other words, this is an adjustment of the range of action of the thermostat and determines the mean temperature which the control mechanism is intended to maintain. This adjustment has nothing to do with the sensitivity or differential of the device which is set when the device is manufactured. This permits a very fine adjustment of the distance between lever 26 and thermostatically actuated rod 18b at the point 27. If in combination with the above I provide a fine adjusting thread between the member 21 and the boss 23, I then arrange for a fine adjustment of the position of the arm 19b which through the relationship between the arms 21a-20 and 27-20 just referred to, gives an even finer adjustment at the point 27. The adjusting knob 24 may be suitably marked to indicate the temperature ranges when the device is calibrated. Note that this puts the indicator at the front of the device in a plane normal to the length of the thermostat rod and easily accessible.

It will be noted that with the improved construction here disclosed there is no adjustment of the thermostat rod itself, but the adjustment is all on the leverage mechanism. The leverage mechanism in its entirety is supported on a single

5 pivot and shiftable about that pivot to vary its relation to the thermostat. Also note that there is no packing necessary on the thermostat rod, thus leaving it perfectly free to find its own position. This is made possible because the adjusting member is located at the point 23 where the adjusting member can be brought out of the casing 10 through an opening which may be suitably packed as by the packing 31 held in place by a gland and this packing does not affect the action of the thermostatic device. In other words this is the only opening through the casing to permit of adjustment and it is arranged at a point where a manually operable part extends through the casing so that the packing does not affect the working of the device but is easily overcome at the time any adjustment is made by the hand of the operator on the knob 24.

10 My improved thermostatic device is so constructed and arranged that I am enabled to manufacture the parts to exact size and dimensions and assemble them in exact relationship very simply so that in mass production of these devices each one will be exactly like the others and easily adjusted to exact operating conditions. This is made possible because all of the operating leverage is suspended from pivot 20 and in the manufacture of the device the points in casing 10 supporting the pin 20 may be jiggled in 15 exact relation to the valve opening 15. The point 27 is exactly located on the lever 26 as pointed out previously by the formation of a slight depression. Also pin 25 may be exactly positioned with reference to pin 20 as will be readily apparent from Fig. 4. Thus I have arranged a 20 device which comprises but a few parts, all of which may be exactly manufactured and when assembled will be in a definite fixed relationship.

25 It will be noted that the line of action of the spring force exerted by spring 30 always extends to the right of pivots 20 and 25 as seen in Figs. 1 and 2. Thus when lever 26 is in contact with rod 18b, spring 30 tends in two ways to turn lever 19 in a clockwise direction to hold that lever against adjusting member 21. The downward thrust of lever 29 against lever 19 exerts one turning force and the tendency of the spring to turn lever 26 counterclockwise about point 27 tends to move pivot 25 and lever 19 clockwise about pivot 20.

30 What I claim is:

35 1. Control mechanism of the class described, comprising the combination with a casing, of a control member, a thermostat, and snap acting 40 operating mechanism connecting said member and thermostat, including three levers supported in said casing and lying generally parallel with each other, one lever forming a support and being fulcrumed near one end to enable it to be set in various positions, a second lever being actuated by the thermostat and being fulcrumed to the support lever at a point spaced lengthwise of the support lever from its fulcrum, said first and second levers extending in the same direction from their respective fulcrums, a third lever being arranged to operate the control member and being fulcrumed on the free end of the first lever and extending toward the first lever fulcrum, and a tension spring connecting the free ends of said second and third levers.

45 2. Control mechanism of the class described, comprising the combination with a casing, of a control member, a thermostat, and snap acting 50 operating mechanism connecting said member and thermostat, including three levers supported

in said casing and lying generally parallel with each other, one lever forming a support and being fulcrumed near one end to enable it to be set in various positions, a second lever being engaged and actuated by the thermostat and being fulcrumed to the first named lever at a point between said thermostat engaging point and the fulcrum of said first named lever, said first and second levers extending in the same direction from their respective fulcrums, the third lever being arranged to operate the control member and being fulcrumed on the free end of the first named lever and extending toward the fulcrum of said first named lever, and a tension spring connecting the free ends of said second and third levers.

3. Control mechanism of the character described in claim 1, including means for adjusting the first lever about its fulcrum to thereby adjust the fulcrum of the second lever transversely to the length of the second lever and thus vary the mean temperature which the control mechanism is designed to maintain.

4. Control mechanism of the character described in claim 2, including means for adjusting the first lever about its fulcrum to thereby adjust the fulcrum of the second lever trans-

versely to the length of the second lever and thus vary the mean temperature which the control mechanism is designed to maintain.

5. Control mechanism of the class described, comprising the combination with a casing, of a control member, a thermostat, and snap acting operating mechanism connecting said member and thermostat, including three levers supported in said casing and lying generally parallel with each other, one lever forming a support and being fulcrumed near one end to enable it to be set in various positions, a second lever being actuated by the thermostat and being fulcrumed to the support lever at a point spaced lengthwise of the support lever from its fulcrum, said first and second levers extending in the same direction from their respective fulcrums, a third lever being fulcrumed at one end and arranged to operate the control member, the free end of said third lever extending toward the first lever fulcrum, a tension spring having one of its ends connected with the free end of said third lever, and the fulcrum of said third lever and the other end of said spring being carried one by said first lever and one by said second lever.
